UNITED STATES PATENT OFFICE.

GEORGE A. JOHNSON, OF CHICAGO, ILLINOIS, ASSIGNOR TO WILLIAM H. MINER, OF CHAZY, NEW YORK.

HIGH-CAPACITY FRICTION SPRING DRAFT-RIGGING.

1,225,715.

Specification of Letters Patent.

Patented May 8, 1917.

Application filed November 30, 1914. Serial No. 874,665.

To all whom it may concern:

Be it known that I, GEORGE A. JOHNSON, a citizen of the United States, residing at Chicago, in the county of Cook and State 5 of Illinois, have invented a certain new and useful Improvement in High-Capacity Friction Spring Draft-Rigging, of which the following is a full, clear, concise, and exact description, reference being had to the accompanying drawings, forming a part of 10 this specification.

This invention relates to improvements in high capacity friction spring draft rigging.

An object of the invention is to provide a 15 draft rigging for railway cars of high capacity and which will have an easy graded action under both buff and draft.

The invention furthermore consists in the improvements in the parts and devices and 20 in the novel combinations of the parts and devices, as herein shown, described or claimed.

In the drawing forming a part of this specification, Figure 1 is a horizontal sectional view of a draft rigging embodying my improvements. Fig. 2 is a vertical sectional view taken substantially on the line 2—2 of Fig. 1. Fig. 3 is a detail perspective view of one of the follower plates employed. 30 Fig. 4 is a view similar to Fig. 1, but showing the gear after a slight buffing action. Fig. 5 is a view similar to Fig. 4 but showing the relation of the parts after a further inward movement of the draw bar and Fig. 6 35 is a view similar to Figs. 4 and 5 but showing the gear under full buff.

In said drawing, 10—10 denote the center sills or draft sills of a car, which may be of any suitable or well known form, and the 40 same have attached thereto rear stops 11—11 and front stops 12—12, the latter being also provided with front limiting stops 13. A draw bar 14 is provided, the same having secured thereto by rivets or other suitable 45 means a yoke 15. Mounted within the yoke is a front follower 16 and a casting A, said casting A comprising a friction cylinder 17 near the forward end thereof and spring compartments 18 and 19. The spring 50 compartment 18 is located in front of the compartment 19 and is separated from the latter by means of an integral intermediate wall or partition 20, said wall 20 being connected to the rear wall 21 of the spring casting by upper and lower horizontal walls 22

and 23. Shoulders 24 are also provided adjacent the rear end of the friction cylinder 17, which shoulders are adapted to engage the limiting stops 13 upon forward movement of the casting. Within the cylinder 17 60 is mounted a friction device which may be of any suitable design and, as shown, the same comprises a plurality of friction shoes 25, wedge 26 and anti-friction rollers 27 between the wedge and the shoes. 65 Mounted within the spring chamber 18 are twin arranged sets of nested springs 28 which at their rear ends abut the partition 20 and at their forward ends bear against a spring follower or cap 29, the 70 latter having a hollow cylindrical forward extension 30 which slides loosely within the rear portion of the friction cylinder 17. The extension 30 is normally spaced from the rear ends of the friction shoes 25, 75 as clearly shown in Fig. 1 and this normal position of the parts is maintained by the preliminary compression spring 31 which fits over a boss on the front face of the follower 29 at its rear end and at its front end, 80 engages inner shoulders 32 on the shoes. The shoes, wedge, preliminary spring and follower 29 are preferably held in assembled relation by means of a bolt 33.

The intermediate wall or partition 20 is 85 perforated at two points, as indicated at 34—34 and through these extend tubular bosses 35 formed integrally with another spring follower 36. Between the follower 36 and the rear wall 21 of the casting A 90 are mounted another set of twin arranged nested springs 37—37. As appears from Fig. 1, the forward ends of the bosses 35 are normally spaced from the follower 29.

The action of the gear is as follows:— 95 Under buff, the front follower 16 is moved inwardly, thus actuating the wedge and friction shoes which are resisted at first by the preliminary spring 31. After this spring has been fully compressed, which is the position of the parts shown in Fig. 4, the front set 28 of the tandem arranged twin sets of springs are operated upon and the friction shoes resisted thereby until such time as the follower 29 comes into engagement with the 100 front ends of the extensions 35, which is the position of the parts as shown in Fig. 5. Upon further inward movement of the draw bar, the rear set of springs 37 are 105 compressed, due to the rearward movement of 110

the follower 36, as shown in Fig. 6. Under draft, the reverse of the preceding described actions takes place, that is, the casting A is moved forwardly and the friction shoes 5 are resisted by the preliminary spring 31, then the springs 28 and finally the springs 37. The gear is held in place by means of a saddle plate 40 attached to the sills by bolts 41.

- 10 From the preceding description it will be seen that the gear is of extremely high capacity, yet the action is easy and gradual, thus insuring easy starting and stopping of trains.
- 15 Although I have herein shown and described what I now consider the preferred embodiment of my improvements, yet I am aware that changes and modifications may be made without departing from the spirit 20 of the invention and all such changes are contemplated as come within the scope of the claims appended hereto.

I claim:

1. In a draft rigging for railway cars, the combination with a friction shell having friction devices coöperable therewith, of a spring case rigid with respect to said shell, said case having two spaced followers rigid therewith, tandem arranged sets of 30 springs within said case, and two movable followers within said case.
2. In a draft rigging for railway cars, the combination with a casting having a friction cylinder, rear wall and intermediate 35 wall, of friction devices coöperable with said cylinder, springs within said casting between the intermediate wall and the friction cylinder, and springs between said intermediate wall and the first named wall.
3. In a draft rigging for railway cars, the combination with a friction cylinder having a spring case formed integrally therewith, said case being divided into two compartments by a rigid intermediate wall, springs 45 in each of said compartments, a movable follower in each of said compartments, one of said followers having extensions into the adjacent chamber and adapted to be engaged by the other movable follower, and friction 50 devices coöperable with the friction shell.
4. In a draft rigging for railway cars, the

combination with a casting having a friction cylinder, rear wall and intermediate wall, of friction devices coöperable with the friction cylinder, a spring follower between the friction cylinder and the intermediate wall, springs between said follower and said intermediate wall, a spring between said follower and the friction devices, another follower mounted within said casting between the rear 60 wall and the intermediate wall thereof and having extensions passing through said intermediate wall, and springs between said follower and the rear wall of the casting.

5. In a draft rigging for railway cars, the combination with a friction shell, friction elements coöperable with said shell, a follower at the inner end of said elements and with which some of the latter are adapted to directly engage, a spring normally in engagement with said follower and exerting pressure thereagainst during all movements of said follower, a second spring in alignment with the first named spring, a second follower coöperable with said second named 75 spring, and thrust means extending from said second named follower toward the first named follower but normally out of engagement with the latter, said thrust means and first named follower coming into engagement 80 after a predetermined movement of the friction elements and the first named follower, whereby said springs come into action in sequence and their resistance to the movements of the friction elements is rendered cumulative. 85

6. As an article of manufacture, a casting having a friction cylinder at one end and a spring casing formed integrally with said cylinder, said casting having an integral wall 90 at the end opposite to that where the friction cylinder is formed, said wall acting as a follower, said casting being provided also with a second integral wall intermediate said first named wall and the inner end of 95 the friction cylinder, whereby to provide two spring chambers within the spring casing.

GEORGE A. JOHNSON.
